SMOKING PIPE

August Pasut, Detroit, Mich.

Application June 22, 1940, Serial No. 341,920

2 Claims. (Cl. 131—215)

This invention relates to smokers' pipes, and particularly to improved means for disposing of the moisture developed by, and incident to, the smoking of a pipe, without permitting the moisture resulting from either the distillation of the tobacco or the salivary discharge of the smoker to enter or return to the mouth from the pipe. As is well known, such moisture becomes loaded with poisons, condensed from the burning tobacco, and these poisons are definitely injurious, as well as unpleasant, if swallowed. Many attempts have been made, involving the use of filters, traps, and other expedients, to dispose of the moisture, pre-condense the tars and other foreign substances, or otherwise guard against poisoning the smoker.

Those pipes previously known which have utilized moisture traps and filters have ordinarily been designed to catch and hold the saliva, together with any moisture distilled from the burning tobacco, both being accumulated in a common trap. With such an arrangement the saliva becomes polluted, and if the trap is not emptied when filled, liquid from the trap, or the overflow of polluted saliva therefrom, is apt to enter the mouth in greater quantities than is possible with an ordinary pipe without a trap. The present invention accordingly aims to provide such a pipe construction having separate traps for collecting and holding the saliva and the liquid condensed from the tobacco, and which keeps the saliva from mingling with and becoming polluted by the poisonous condensation productions, so that even should the user neglect to empty the saliva trap, it would be impossible for him to draw polluted saliva into his mouth, while the nature and location of the condensation trap and the viscous character of the condensation products make it impossible for these to run or be drawn into the mouth at any time.

It is common practice in the construction of pipes to allow the saliva to mingle with the smoke throughout the length of the stem. The protection afforded by such a pipe, even though equipped with a trap, is imperfect because of the tendency of poisons to condense in the saliva as it runs through the stem. Even though only a small quantity of the polluted saliva is drawn back into the mouth with the smoke at the next inhalation, the cumulative effect is extremely injurious. Normally the quantity of saliva to be disposed of greatly exceeds the quantity of liquid distilled from the tobacco. With the foregoing in mind, another important object of the present invention is to provide an improved pipe construc-

tion so designed that the smoke cannot mingle with the saliva to any material extent, and which accordingly prevents condensation of appreciable amounts of poisonous material in the saliva. The invention contemplates, further, the complete separation of the salivary discharge from the smoke throughout virtually the full length of the stem, commencing at a point close to the mouth of the smoker.

Still another object is to provide such a pipe having separate traps for condensate and for salivary discharge, incorporating common sealing means for the separate traps above referred to, whereby, by removal of a single sealing element, both traps may be cleaned at once.

Other objects and advantages will be apparent from the following description, wherein reference is made to the accompanying drawing illustrating a preferred embodiment of my invention and wherein similar reference numerals designate similar parts throughout the several views.

In the drawing:

Figure 1 is a substantially central longitudinal section, upon an enlarged scale, showing a pipe constructed in accordance with the present invention.

Figure 2 is a sectional view taken in the same plane as Figure 1 with the bowl and part of the stem portion broken away, and showing the mouthpiece and stem portions separated from one another.

Figure 3 is a sectional view taken substantially on the line 3—3 of Figure 1 and looking in the direction of the arrows.

Referring now to the drawing, reference character 10 designates the bowl portion of my improved pipe. The bowl, together with the stem 12, may be formed of briar, although the material used is subject to variation. A removable mouth-piece 15 is attached to the end of the stem. Two longitudinal passages 18—20 are formed in the stem, passage 18 being smaller than and arranged above passage 20, and communicating with a bore 19 entering the bottom of the bowl in the usual manner. A portion of passage 20 nearest bowl 10 is enlarged to provide a reservoir of substantial size for saliva, and a continuation 22 of passage 20 extends through the mouthpiece 15 and is in sealed engagement with the passage 20 when the mouthpiece is attached, as shown in Figure 1. The central tubular portion 23 of the mouthpiece defining the channel 22 is connected to the hollow interior of the mouthpiece only by a small passage 25, located in the top of the channel and close to

the end of the mouthpiece. The hollow interior 16 of the mouthpiece communicates with the smoke passage 18 when the mouthpiece is attached to the stem. An angular bore 26 beneath the bowl connects passage 18 at its opposite end with the enlarged passage 21 forming the saliva reservoir. Passage 21 is open at its end beneath the bowl, and tapped, the threads extending inwardly beyond the open end of the passage 26. A plug 30 is threaded thereinto. The plug is 10 centrally cut away, as indicated at 31, to provide an enlarged space for the reception of condensation products, which drop thereto through the passage 26. The plug at the same time seals off the saliva trap 21, as shown in Figure 1. The head of the plug is provided with a squared end 33 adapted to receive a wrench (unshown) by means of which it may be conveniently removed for cleaning.

I am aware that the invention may be embodied in other specific forms without departing from the spirit or essential attributes thereof, and I therefore desire the present embodiment to be considered in all respects as illustrative and not restrictive; reference being had to the appended claims rather than to the foregoing description to indicate the scope of the invention.

I claim:

1. A smoking pipe construction comprising in combination with a bowl, a stem attached to the bowl, a mouthpiece removably attached to the stem, interconnecting chambered portions in said stem and mouthpiece forming a continuous smoke passage extending therethrough and communicating with the bowl, and also forming a saliva compartment separated from said smoke passage and extending substantially the length of said stem and mouthpiece, at least a part of the smoke passage within the mouthpiece lying above the saliva compartment, means defining a passage connecting said smoke passage and saliva compartment within and near the free end of the mouthpiece, means defining a second connecting

passage providing communication between said saliva compartment and smoke passage at a point near said bowl, and common plug means for sealing said saliva compartment on opposite sides of said second connecting passage, said plug means having a recess forming a well for liquid condensed in the bowl and/or smoke passage as well as for any liquid material melted or otherwise resulting by reason of the burning of tobacco in the bowl.

2. A smoking pipe construction comprising in combination with a bowl and stem, a mouthpiece removably attached to the stem having a central passage throughout its entire length, a surrounding chamber extending throughout the major portion of the mouthpiece, and an opening connecting said chamber and central passage adjacent the rear extremity of the mouthpiece, the stem having a pair of separated passages extending 15 throughout the length of the stem, the lower of such passages communicating with the central passage of the mouthpiece to form a saliva compartment and the upper of said stem passages communicating with the upper portions of the surrounding chamber in the mouthpiece, an inclined passage at the forward extremity of the pipe stem connecting the forward extremities of the upper and lower stem compartments, a passage from the bowl extending into such inclined passage, means for sealing the forward extremity of the saliva compartment of the stem rearwardly of said inclined passage, and additional sealing means spaced from the first mentioned sealing means and located at the extreme forward extremity of the saliva compartment, whereby a well for liquid condensed in the bowl and/or smoke passage as well as for any material melted or otherwise resulting by reason of burning in the bowl is formed in the lower extremity of said inclined passage and between said sealing means.

AUGUST PASUT.
